COMBINED ELECTRIC TESTER, LAMP, AND SMOKER'S OUTFIT

Raymond Zuazua, New York, N. Y.

Application June 1, 1953, Serial No. 25,289

Term of patent 7 years

(Cl. D48—20)

To all whom it may concern:

Be it known that I, Raymond Zuazua, a citizen of the United States, residing at New York, in the county of New York and State of New York, have invented a new, original, and ornamental Design for a Combined Electric Tester, Lamp, and Smokers' Outfit, of which the following is a specification, reference being had to the accompanying drawing, forming part thereof.

In the drawing:

Fig. 1 is a front perspective view of a combined electric tester, lamp, and smokers' outfit, showing my new design; and

Fig. 2 is an exploded rear perspective view of the same.

I claim:

The ornamental design for a combined electric tester, lamp, and smokers' outfit, as shown.
